DESIGN FOR A COMBINED TUFTED AND EMBROIDERED FABRIC

Morris Mitler, New York, N. Y.

Application April 20, 1937, Serial No. 68,881

Term of patent 3½ years

To all whom it may concern:

Be it known that I, Morris Mitler, a citizen of the United States of America, residing in Manhattan, county of New York, and State of New York, have invented a new, original, and ornamental Design for a Combined Tufted and Embroidered Fabric, of which the following is a specification, reference being had to the accompanying drawings, forming part thereof, wherein,

Figure 1 is a front view of a combined tufted and embroidered fabric showing my new design.

Figure 2 is a rear view of the combined tufted and embroidered fabric shown in Figure 1.

I claim:

The ornamental design for a combined tufted and embroidered fabric, substantially as shown.

MORRIS MITLER.
